UNITED STATES PATENT OFFICE.

HARRY SWINGLEHURST, OF PHILADELPHIA, PENNSYLVANIA, ASSIGNOR TO SCOTT & WILLIAMS, INCORPORATED, OF PHILADELPHIA, PENNSYLVANIA, A CORPORATION OF NEW JERSEY.

YARN-FEEDING DEVICE FOR KNITTING-MACHINES.

1,124,076.

Specification of Letters Patent.

Patented Jan. 5, 1915.

Application filed July 13, 1912. Serial No. 709,273.

To all whom it may concern:

Be it known that I, HARRY SWINGLEHURST, a citizen of the United States, residing in Philadelphia, Pennsylvania, have invented certain Improvements in Yarn-Feeding Devices for Knitting-Machines, of which the following is a specification.

My invention relates to that class of knitting machines in which, by the operation of automatic mechanism, one yarn is substituted for another at different stages in the operation of the machine, those features of construction which constitute my invention being fully described and specifically 15 claimed hereinafter.

In the accompanying drawings—Figure 1 is a side elevation, partly in section, of sufficient of a knitting machine of the type to which my invention relates to illustrate 20 said invention; Fig. 2 is a horizontal section on the line *a*—*a*, Fig. 1, illustrating those parts of the attachment to which my invention particularly relates; Fig. 3 is a vertical section on the line *b*—*b*, Fig. 2; Fig. 4 is 25 a horizontal section on the line *c*—*c*, Fig. 3; Fig. 5 is a plan view of one of the yarn-feeding guides and of the mechanism for operating the same; Fig. 6 is a similar view 30 of another yarn guide and its operating mechanism, illustrating the same in different position from that shown in Fig. 5; Fig. 7 is a section on the line *d*—*d*, Fig. 2, illustrating yarn severing and nipping devices and a yarn placing device acting in 35 cooperation with the yarn feeding devices; Fig. 8 is a section on the line *e*—*e*, Fig. 1, and Fig. 9 is a view of the cam for actuating the yarn nipping and placing devices.

In Fig. 1 of the drawing, 1 represents 40 part of the lower fixed frame of the machine and 2 part of a fixed standard projecting upwardly therefrom, the lower frame 1 having bearings for the various shafts, whereby rotating or reciprocating 45 movement is imparted to the needle cylinder of the machine; this frame also carrying the pivot stud 3 for a lever 4. A coiled spring 5 tends constantly to impart movement in one direction to this lever and 50 movement in the opposite direction is imparted thereto by means of a rocking cam 6 which acts upon an anti-friction roller on a stud 7 secured to one arm of the lever, as shown in Fig. 1, rocking movement being

imparted to said lever 6 in any desired 55 manner, as for instance, by mounting it upon the hub of a rocking lever such as shown at 20 in Letters Patent 697,953, dated April 15, 1902.

When the lower arm of the lever 4 has 60 been raised by the action of the cam 6 against the tension of the spring 5, an anti-friction roller mounted on a stud 8 located near the outer end of said lower arm of the lever 4 is engaged by a trigger lever 9, 65 mounted at 10 on the fixed frame of the machine and having a hooked arm 11 for engaging the roller on the stud 8, and another arm 12 for being acted upon by a series of cams 13 carried by a pattern drum 70 14 to which step by step or other intermittent movement of partial rotation is imparted by any of the ordinary means known to the art, and therefore not necessary to be shown and described. When, therefore, the 75 lower arm of the lever 4 is raised by the cam 6 it will be caught and held in the raised position by the hooked arm of the trigger 9 until such time as one of the cams 13 on the drum 14 strikes the arm 12 of the 80 trigger lever, whereupon the arm of the latter will be withdrawn from engagement with the roller on the stud 8 and the lever 4 will be permitted to assume its other extreme position under the pull of the 85 spring 5.

Each of the cams 13 forms part of a yoke 13^a which is clamped to the drum 14 by means of a screw 13^b, as shown in Fig. 8, so that the cams can be readily applied to or 90 removed from the pattern drum and can be disposed thereon in any relations which the desired operation of the machine may suggest.

A swinging head 15 at the upper end of 95 the lever 4 is connected by a universally jointed link 16 to a similar swinging head 17 at the lower end of a stud 18, which projects downwardly from an arm 19 on a sleeve 20, the latter, together with other 100 sleeves referred to hereinafter, being free to turn on a vertical shaft 21 which is mounted in a bearing in a bracket 22 secured to and projecting from the fixed post or standard 2 of the machine, as shown in Fig. 105 2. Rocking movement will, therefore, be imparted to the arm 19 by the lever 4 at certain intervals during the cycle of operations

performed by the machine, these intervals being determined by the position of the cams 13 on the pattern drum 14.

To a stud 23 on the arm 19 are pivoted two pawls 24 and 25, the tooth of the pawl 24 being adapted to engage with rectangular notches in the periphery of a disk 26 whose hub 27 is pinned or otherwise secured to the lower portion of the vertical shaft 21, the upper portion of said shaft being pinned or otherwise secured to the hub 28 of a disk 29 which rests upon the top of the bracket 22 and thus provides for the vertical support of the shaft 21 and of the parts carried thereby. The tooth of the pawl 25 engages with the peripheral notches of the disk 26 and also with the cam face of a disk 30 which is maintained in a fixed position above the disk 26 by reason of the fact that its hub 31 is secured to a sleeve 32 depending from the bracket 22 and constituting part of the bearing for the shaft 21, as shown in Fig. 3.

The tooth of the pawl 25 is, as shown at 25 33, in Fig. 1, longer than the tooth of the pawl 24 in order that said tooth 33 may engage both with the disk 26 and with the disk 30, while the tooth of the pawl 24 engages with the disk 26 only. The pawls 24 and 25 are held in contact with the peripheral faces of their respective disks by means of a spring 34 which connects studs 35 projecting from the pawls, as shown in Fig. 4.

The swinging movement imparted to the 35 arm 19 is of sufficient extent to cause the pawl 24 to impart to the disk 26 movement to the extent of one-quarter of a turn, the controlling cams mounted on the shaft 21, and which will be hereinafter referred to, 40 being of such configuration as to require a movement of this extent, but controlling cams of different configuration might be used which would require a movement of the disk 26 and shaft 21 to the extent of less than one-quarter of a full turn, in which 45 case the extent of movement of the arm 19 would be modified accordingly.

A frictional retarding device to prevent 50 overrunning of the disk 26 is provided by a tapering lug 36 carried by a spring arm 37 projecting from the bracket 22 and engaging correspondingly tapered notches 38 formed in the periphery of a disk 39 which is secured to the underside of the disk 55 26, as shown in Fig. 3.

The use of the pawls 24 and 25 is intended 60 to positively lock the disk 26 in position after each of its movements, such locking being effected by reason of the engagement of the abrupt forward face of the tooth of the pawl 24 with the abrupt forward wall of one notch in the disk 26 and the simultaneous engagement of the abrupt rear face of the tooth 33 of the pawl 25 with the abrupt rear wall of the next succeeding notch of

said disk 26, as shown in Fig. 4. In order, however, that the pawl 25 may not impart rearward movement to the disk 26 on the backward swing of the arm 19 the cam 30 acting upon the upward portion of the tooth 33 of the pawl 25, lifts said tooth out of the notch in the disk 26, with which it was formerly in engagement, just before the completion of the forward swing of the arm 19, and the tooth 33 is therefore held out of engagement with said notch or disk 26 until, on the backward swing of the arm 19, it has been carried beyond range of said notch. It will not, therefore, engage with the following notch until the rearward swing of the arm 19 has been completed and the tooth of the pawl 24 is in position to enter the preceding notch.

Mounted upon the disk 29 are three cams 40, 41 and 42, which act respectively upon three levers 40^a, 41^a and 42^a, mounted upon a stud 43 on the bracket 22 and each connected by means of a link 44 to that member of the yarn guiding mechanism with which it co-operates. The cams 40 and 41 act, respectively, through the levers 40^a and 41^a and the connecting rods, upon levers 40^b and 41^b, these levers carrying the usual yarn guides *w*, as shown in Fig. 2.

Each of the cams 40 and 41 has two low portions *x* and two high portions *y* and these cams are set upon the disk 29 at an angle of 90° to one another so that the low portion of one cam will correspond with the high portion of the other cam. The low portion of the cam corresponds with that position of the yarn guide and its lever during which yarn is being fed to the needles, as shown for instance in Fig. 6, and the high part of the cam corresponds with that position of the yarn guide and its lever during which the guide is withdrawn from the needles and fails to feed yarn thereto, as shown for instance in Fig. 5, hence, owing to the reverse disposition of the cams 40 and 41, each quarter turn of the shaft 21 will cause a reversal in the position of the yarn guides, the one formerly in feeding position being moved to non-feeding position, and vice-versa.

It will be noted on reference to Figs. 5 and 6 that each of the low portions *x* of the cams 40 and 41, corresponding to the active position of the yarn guide lever, is of greater extent than the high portions *y* which correspond to the inactive position of the yarn guide lever, hence when the cams are moved the previously inactive lever will be moved to the feeding position before the previously active lever is moved out of feeding position so as to prevent any break in the feeding of the yarn to the needles.

The levers 40^a and 41^a are pivotally mounted upon a stud 45 carried by an arm 46 projecting from any suitable support

provided by the knitting machine structure, as for instance, the latch guard ring 47 with which such structures are usually provided. Another arm 48 on the ring 47 carries a fixed shearing and nipping blade 50 and a pivoted shearing and nipping blade 51 which cooperates with said fixed blade 50, as shown in Fig. 7. The pivoted blade 51 has connected to it a pivoted rod 52 which passes through a stud 53 on a plate 54, the outer end of said rod 52 being threaded and provided with nuts 55 which can be adjusted to different positions thereon and which serve to lock each other in position after such adjustment. The rod 52 is curved to accord with the arc in which the stud 53 swings.

The plate 54 is carried by the free end of a lever 42^b which also carries a projecting finger 56 forked at its forward end, as shown in Fig. 7. The lever 42^b is connected by one of the links 44 to the lever 42^a which is acted upon by the uppermost cam 42, as shown in Fig. 2, and by the action of the said cam 42 quick forward and backward movements are imparted to the stud 53 and finger 56 whenever one of the thread guides *w* is moved into operative position and the other out of operative position. The cam 42 has four high points and four low points and the lever 42^a is acted upon by a high point of the cam at each of the successive positions of rest of the latter, this high point representing the retracted position of the stud 53 and finger 56, as shown in Fig. 7. On every movement of the shaft 21, therefore, back and forth movements will be imparted to the stud 53 and finger 56, one of the yarn guides *w* will be swung forwardly into operative position and the other yarn guide *w* will be swung backwardly into inoperative position. Whenever the yarn guide is moved to inoperative position the yarn extending from the needles of the machine to said inoperative yarn guide will be laid between the fixed and movable cutters 50 and 51, the latter, on the forward movement of the stud 53, being permitted to open so as to receive the yarn and on the backward movement of said stud being closed so as to sever and nip the yarn. The finger 56 moves forwardly with the stud 53 and its forked end engages the yarn which formerly extended from the blades 50 and 51, to the inoperative yarn guide and pushes said yarn forwardly into range of the needles of the machine, as said formerly inoperative yarn guide is moving to operative position.

Owing to the conformation of the cam 42, the finger 56 moves more quickly than the yarn guides so that the formerly inoperative yarn is caused to engage with said needles before the formerly operative yarn guide has been retracted so far as to with-

draw its yarn from the needles, hence there is no likelihood of a failure of one yarn to reach the needles before the other yarn is withdrawn therefrom, as there might be if the engagement of the formerly inoperative yarn with the needles was dependent upon the movement of the yarn guide *w* itself from inoperative to operative position, the desideratum in these cases being to cause the incoming yarn to overlap the retiring 70 yarn for a short distance. By the time the retiring yarn guide reaches its inoperative position the inserting finger 56 has also been fully withdrawn again and is in position to receive in its forked forward end the yarn 75 extending from said inoperative yarn guide to the cutting and nipping blades 50 and 51.

The action of the cams 40 and 41 upon the levers 40^a, 41^a, 40^b and 41^b, is to withdraw the yarn guides from operative to inoperative position, movement in the opposite direction being effected by coiled springs 60 connecting studs 61 on the links 44 with studs 62 on the projecting arm of the bracket 22, as shown in Fig. 2, and 85 the action of the cam 42 on the levers 42^a and 42^b tends to withdraw the stud 53 and finger 56 to inoperative position, the movement of these parts to operative position being effected by a similar spring 60 connecting similar studs on the link 44 and bracket.

The cam 42 has adjacent to each high point on the ascending side of the cam a face 63 at a lesser angle than the face 64 100 which constitutes the beginning of the ascending side of the cam, the purpose of this change of angle being to reduce the speed of the backward movement of the stud 53 as it approaches the limit of such backward 105 movement so as to lessen the force of the blow of said stud upon the nuts 55 and also to effect a relatively slow closing movement of the blades 50 and 51 so as to insure the laying between the same of the yarn extending from the needles to the yarn guide which is just being rendered inoperative.

I claim:

1. The combination, in yarn feeding devices for knitting machines, of a plurality 115 of yarn guides, means for moving said yarn guides to operative or inoperative position, means for nipping the yarn from the guide which is being moved to inoperative position, a finger for acting upon the yarn from 120 the guide which is being moved to operative position and causing said yarn to engage with the needles, and means independent of the yarn guide for moving said finger at a higher rate of speed than the yarn 125 guide whereby it will apply the yarn to the needles before the yarn guide has reached its operative position.

2. The combination, in a yarn feeding device for knitting machines, of a plurality of 130

yarn guides, means for moving said yarn guides to operative or inoperative position, means for nipping the yarn from the guide which is being moved to inoperative position, a finger for acting upon the yarn from the guide which is being moved to operative position and causing said yarn to engage with the needles, said finger and the devices for operating the yarn nipper being mounted on one and the same carrier, and means for moving said carrier independently of the yarn guides so as to cause the finger to apply the yarn to the needles before the yarn guide has reached its operative position.

3. The combination in a yarn feeding device for knitting machines, of a plurality of yarn guides, means for moving the same into and out of operative position, a finger for acting upon the yarn from the guide which is being moved to operative position and causing said yarn to engage with the needles, a movable carrier for said finger, yarn nipping blades, a swinging operating

device therefor mounted upon the same carrier as the finger, and an adjustable connection between the said swinging device and the movable member of the nippers.

4. In yarn feeding devices for knitting machines, the combination of a plurality of 30 yarn guides, means including cams for moving said yarn guides to operative or inoperative position, and means for imparting movements of partial rotation to said cams, said means including a disk with notched 35 periphery, a swinging arm with right and left pawls thereon for engaging successive notches in said disk, and a cam for holding said left hand pawl out of position to engage a notch when it first begins to move 40 backwardly.

In testimony whereof, I have signed my name to this specification, in the presence of two subscribing witnesses.

HARRY SWINGLEHURST.
